UNITED STATES PATENT OFFICE

HOXIE H. HUMPHREYS, OF PHOENIX, ARIZONA

COOLING SYSTEM

Application filed March 19, 1928. Serial No. 262,803.

The present invention relates to a cooling and ventilating system of a type especially adapted, for example, to the cooling and ventilating of an enclosed space, such as a room, or a building, of any description.

One object of the invention is to provide such a cooling system which is marked by a high chilling efficiency and ease of installation.

10 A further object of the invention is to provide a cooling system of the kind described, wherein the amount of chilling may be readily regulated as desired.

15 A still further object of the invention is to provide means whereby atmospheric air is subjected to a series of chilling operations to bring the said air to a desired cooling temperature before it is introduced into the room or building which is to be cooled.

20 Other objects and advantages will become apparent from the following description of the invention, which description is to be regarded as illustrative only, as the specific form of the invention is obviously capable of wide modifications and changes without departing from the conception and scope of the invention.

It is well known that in climates where summer temperatures are high, that it is desirable to cool rooms and buildings, especially where public gatherings are held, or where large numbers of persons are housed, as in modern apartment buildings, so that the outdoor temperatures will not become oppressive on the inside of the room or building. Cooling systems are already widely employed in auditoriums, theaters, and other places of public meeting, but all of these systems are open to the disadvantage that the cooling is not efficiently done, and if the air inside of the room or building is cooled to a sufficient extent to be comfortable, the cost of operation of the systems becomes excessive. The system of the present invention provides a means for thoroughly refrigerating the cooling air at a relatively low cost of installation and operation, and the system can also be readily produced in any desired size, so that any kind of building, large or small, may receive it.

Briefly outlined, the invention comprises an inlet for atmospheric air, and means for cooling this air, either in a single stage or in a series of distinct stages or steps, wherein the cold is successively increased, the temperature of the final stage being brought, if desired, substantially below the freezing point of water, the amount of chilling being regulatable in accordance with the temperature of the air in the space to be cooled.

55 The invention will be more clearly understood from the following description, reference being made to the accompanying drawings, in which

Fig. 1 shows a longitudinal diagrammatic sectional view of one form of the installation, where the cooling is carried out in a single stage,

60 Fig. 2 is a section taken on the line 2—2, Fig. 1,

Fig. 3 is an enlarged diagrammatic horizontal section of one of the intermediate cooling units of a multi-stage installation,

65 Fig. 4 is a diagrammatic sectional view through the unit of Fig. 3, along the line 4—4 of Fig. 3, but on a reduced scale,

70 Fig. 5 is a diagrammatic plan view of one form of a complete assembly of a multi-stage installation,

75 Fig. 6 is a diagrammatic sectional view of the installation of Fig. 5, taken along the line 6—6 of Fig. 5,

Fig. 7 is a plan view of the final refrigerating unit of a multi-stage installation,

80 Fig. 8 is a sectional view of the unit of Fig. 7, taken along the line 8—8 of Fig. 7,

85 Fig. 9 is a view similar to Fig. 8, but taken at right angles thereto, along the line 9—9, Fig. 7, and indicating, diagrammatically, the complete assembly of the refrigerating means of the final unit of a multi-stage installation,

90 Fig. 10 is a view similar to Fig. 1, the cooling means being omitted.

95 Referring more particularly to the drawings, the installation of Fig. 1 is a simple means of cooling atmospheric air, and for introducing the cooled air into the space to be cooled. The installation of Fig. 1 is a single stage cooling arrangement. In the figure, a

pipe of a size indicated by the probable necessities of the installation, indicated at 10, serves as the air intake for the room or building. This pipe is of any convenient shape, and is illustrated as having an upturned inlet end portion 11 forming a stand pipe the inlet being sufficiently high above the grade line 12 to prevent undue admission of dust to the pipe 10, this pipe being also non-rusting, for reasons hereafter apparent. The delivery end of the pipe 10 is conveniently shaped to deliver air, cooled in its passage through the pipe 10, into the room or building to be cooled. The delivery portion of the pipe 10 is generally indicated at 13, which is shown as entering a room or building through the partition 13a. The pipe 10 is surrounded over substantially all of its length with a porous water absorbent material, preferably of a permanent character, such as sand, charcoal, coke, etc., this material being applied with a cementing material as a binder, or it may be molded in place, or secured in any other convenient manner to prevent accidental displacement from the pipe. This layer of material is indicated at 14, and is of sufficient thickness to absorb a substantial quantity of water while permitting the ready evaporation of the same, as will be hereafter pointed out. The end 13 may be provided with a heat insulating portion, or layer, similar to the layer 14, of required extent and thickness, but being wholly optional, is not shown on the drawings.

Surrounding the pipe 10 is a second pipe 15, the pipe 15 being spaced from the pipe 10 to form an annular space 16 between the two pipes. As shown, the pipes 15 and 16 are similar in shape, and are conveniently concentrically placed. The pipe 15 is made of non-rusting material, such as rust-proofed sheet metal, or terra cotta, or any other suitable non-rusting material. The outer surface of the pipe 15 is covered with a layer of porous material, such as porous concrete, or absorbent material such as is used in filters. This layer of material is held in place by any desired means, but perforated non-rusting sheet metal is preferred for this purpose. The layer of absorbent material is indicated at 16a.

It will be noticed from the drawings that the intake end 17 of the pipe 15 is conveniently adjacent the discharge end of the pipe 10, and that the delivery end 18 of the pipe 15 conveniently opens into the open air adjacent the inlet end 11 of the pipe 10. This arrangement permits a circulation of a cooling medium between the two pipes in a direction opposed to the direction of flow of air in the pipe 10. This cooling medium may conveniently be air exhausted from the space or room being cooled. Any arrangement giv-

ing this effect will be satisfactory, and the purpose thereof will be indicated below.

The pipe 15 opens into a supply of relatively dry air, either, as at 19, through the foundation work of the building and into the cellar thereof, or the pipe 15 may be apertured, as at 20, to receive the air passageway 21 opening into the open air, or into the space being cooled or ventilated. A fan or other type of blower 22 is provided adjacent the intake end of the pipe 15 to draw air through the said intake and to expel it from the delivery end 18. Similarly, there is provided in the delivery end 13 of the pipe 10, a fan or blower 23 to draw air through the pipe 10 and to discharge the said air into the space to be cooled.

Within the space 16 between the pipes 10 and 15, there is placed the spray or drip pipe 24, perforated in such a way that it sprays or drips a liquid (water) upon the absorbent material 14 in a quantity sufficient to keep the material damp or wet at all times. Dry air, blown through the space 16 by the fan 22 and over the wet surface of the absorbent material 14, causes a rapid evaporation of the liquid contained in the material 14, thus causing a marked cooling of the pipe 10.

It will be seen that the system is preferably installed below the grade line at a convenient depth, for substantially its entire length, the ground above the pipes serving as an efficient heat insulating layer. The layer 16a about the pipe 15 is entirely optional, but it may be advantageous where there is moisture present in the ground, as the layer 16a would absorb and retain some of the moisture close to the pipe, and assist in cooling the entire system.

Instead of employing dry air circulation around the pipe 10, cold water may be employed, by sealing the end 19 by means of a door or other medium, and introducing cold water through the inlet 21. The water would be discharged through an outlet, not shown, in pipe 15, placed at the grade line. If water circulation be employed, the layer 14 is preferably omitted. Water may be conveniently supplied from the final unit of the system hereafter described, if so desired.

For a multi-stage installation the air from the unit just described may be led into a cooling coil instead of directly into the space being cooled. This arrangement is shown in Fig. 3. Here the pipe 10 is continued into the portion 25 of the coil 26, instead of terminating in the discharge end 13, as shown in Fig. 1. The fan 22, aperture 20, and passage 16 of the pipe 15 are also omitted, the pipe 15 connecting at 27 with further cooling provisions, as illustrated in Fig. 3. Here is provided a chamber, preferably a basement room, designated as 28, which may be of any required size and of any convenient configuration. Around the sides of this room a pipe

26, of water proof material, is laid, coil upon coil, until the room has been filled or until the desired length of pipe has been laid. The coil 26 is spaced from the walls 28, as shown, 5 and adjacent each side of the coil there is placed a metal screen or perforated sheet metal members, indicated as 29. The space between these members is filled with an absorbent material 30, conveniently of the same 10 material as described above. Inside of the inner screen member 29, and at any desired distance therefrom, there is situated a wall 31 of air and water proof material, and forming an air and water impervious connection 15 with the floor of the chamber 28. It will therefore be seen that spaces for cooling fluid are provided on both sides of the coil 26, these spaces being indicated by 32 and 33, which spaces are in communication with 20 each other. The circulating cooling fluid may be air, introduced by a blower which may be of a type similar to 22 in Fig. 1 and located in housing 34 through the inlet 35, and forced through the spaces 32 and 33 25 around the coils 26, and out through the outlet 36 thence to the open air, as by the space 16 in Fig. 1. This air may conveniently be taken from the space or room being cooled.

Instead of air, water may be employed as 30 the cooling medium, where convenient, similarly as described in connection with the device of Fig. 1. When water is so employed, it may be admitted through any convenient inlet, not shown, at the bottom of the chamber 35 28, and allowed to flow out of the top of the chamber, or vice versa, as the individual installation may require. When the installation is in a basement below the grade line, it is preferred to admit the air being cooled at 40 the top of the coil 26, passing it downwardly through the turns of the pipe to the bottom of the coil, where it leaves the cooling unit and goes directly to the distributing head, thence to the room or rooms to be cooled. As 45 it is introduced into the coil 26, the air being cooled is several degrees warmer than the cooling fluid, which is heated by the warmer air in the coil, and as the cooling fluid leaves the unit, it is relatively warmer than when 50 it entered. In this manner, the cooling medium is coldest at the bottom where the cold air is leaving the coil 26, thus assuring the maximum of cooling efficiency. If desired, baffles 37 and 38 may be placed within the 55 spaces 32 and 33 to cause eddies and whirls in the cooling medium, thereby facilitating the cooling action through increasing the area of contact. The cold water may be conveniently supplied from the refrigerating 60 unit next to be described, and if water is employed as the cooling medium, the blower housing 34 and its enclosed blower are omitted, and circulation of water established between this unit 28 and the refrigerating unit 65 now to be described.

Reference is now had to Figs. 5 to 9 inclusive. After being subjected to the cooling action of the unit 28, the air being cooled passes from the coil 26 through the passage 39, where it is forced by a blower 40 into a 70 coil 41 and then into a distributing head 42, thence into the room or rooms being cooled. The coil 41 is of any desired length and is enclosed in a chamber 43 of any required size and convenient shape, of water proof construction. In the center of the floor of the chamber there is provided a pit or a tank 44, and at the bottom of this there is provided a sump hole 45. In this sump hole there is placed a water supply pipe 46, which extends horizontally through the wall of the chamber 43 from the pump 47 to a point directly over the sump hole 45. From this point it extends downwardly to a point near the bottom of the sump hole, terminating in 80 a screened foot valve 48. The pipe 46 supplies water to the pump 47, from which it is forced through pipe 48 to the spray head 49. Water is placed in the tank 44, and it therefore circulates through the pipe 46 to the 85 pump 47, through pipe 48 to spray head 49, where it is sprayed over the coil 41, thus cooling the air passing through this coil to the distributing head 42. In practice a brine solution is usually placed in the tank 44, instead of pure water, since lower temperatures can be obtained with brine without 90 freezing.

This brine solution may be cooled artificially, either by placing blocks of ice in the tank 95 44, or preferably by placing a cooling unit of a commercial electric refrigerator therein. This unit is represented at 50, and any unit of the standard makes of electric refrigerator may be employed. The unit 50 is connected 100 to its refrigerant compressor 51, placed outside of the chamber 43, in any desired manner, typified by the pipes 52 and 53.

When ice is used, sufficient brine solution is placed in the tank 44 to float the ice. When 105 a refrigeration system is employed, sufficient brine should be placed in the tank 44 to submerge the refrigerating unit 50. The cold brine naturally cools the entire chamber 43 to a very considerable extent, which of course 110 cools the coil 41; and this cooling action is highly accentuated by the fact that the refrigerated brine is pumped through the spray head 49 and is thus distributed over the coils, returning to the tank by gravity. The 115 air being admitted to the space to be cooled is therefore made as cold as desired, since the temperature of the refrigerating coils is thermostatically controlled, as is customary with electric refrigerators of standard make, 120 and the freezing point of the brine solution is controlled by its concentration. The brine (or water) may be employed as the cooling agent in the other units of the system, if desired, it being circulated therethrough and 125 130

returned to the tank 44 in a closed cycle. Any modifications of the system which may be required will be obvious to anyone skilled in the art. This system of refrigeration may be applied also to chamber 28 in like manner, if desired.

In Fig. 6 it will be seen that the refrigerating liquid may be pumped from the refrigerating tank, 44, through the pipe, 54, by means of pump 55 and introduced over the coil 26 as through a spray head 56, although any other means of introducing this liquid may be employed.

The brine is circulated back into the chilling tank 44, being withdrawn through the pipe 57, pump 58, and into the tank 44 through the orifice 59. The pumps are, of course, independently operative from any suitable source of motive power.

It will therefore be seen that the installation just described subjects the air to be cooled to a series of successive cooling steps of progressively increasing intensities, and it will also be obvious that the amount of cooling in any stage or stages may be regulated at will.

Obviously also if there be convenient a constant source of cold water this may be employed as the cooling agent for the air, and then the refrigerating elements described may be dispensed with by permitting water to flow through the chamber 43 and around the coils 41, either entering the chamber at the top and leaving it at the bottom, or preferably entering at the bottom and leaving at the top.

Also the circulating system described here may be omitted, if desired, the cooling effect then being obtained by filling the chamber with brine until the coil 41 is immersed, the brine being cooled by ice or by the refrigerating unit, as above set forth.

If it is considered that only a relatively slight degree of cooling is desired, the simple installation of Fig. 10 is adaptable. This is simply the arrangement of Fig. 1 with the outside pipe and spray omitted. It consists of the pipe 54, shaped conveniently as shown, with the intake at 55 and the outlet at 56, the pipe entering the room or building through the partition 57, and being provided with a fan or blower 58 to draw atmospheric air through the pipe and to discharge it into the space to be cooled. In Figs. 1 and 10 the ends of the pipes exposed to the atmospheric air are protected by the cover 59.

The fans and blowers described in connection with the system are desirable as they assure a positive circulation of air through the system. However, when the building to be cooled and ventilated is properly provided with registers at proper places, and with proper exits at the top of the building through which hot air can escape, and the cooling elements are properly installed, the air will flow freely through the cooling sys-

tem of its own accord, induced by the thermosyphon principle. The hot air in the building will escape therefrom, and cold air will come through the cooling system to replace the hot air.

It will be further understood that while the respective units of the system are shown as being installed below grade line, the system, or any element thereof, used separately, will give equally as good results above ground when installed in a properly insulated room whether it be on the ground floor or in the top story of a modern "sky-scraper".

It is understood that the above illustrations are examples only of suggested forms of the system and units thereof, as obviously many modifications thereof are possible without departing from the inventive concept, and it is desired to comprehend within the scope of this invention any changes necessary to adapt it to varying conditions and uses.

What is claimed is:

1. A multi-stage refrigerating system comprising the combination with an intake conduit, of a cooling conduit substantially surrounding the intake conduit, and spaced therefrom, a porous absorbent wrapping for the intake conduit, liquid spraying means between the conduits, means in each conduit for circulating air therethrough in counter-currents, means for continuing the intake conduit unbrokenly into each succeeding unit of the system, and means for circulating the refrigerating fluid in a continuous closed cycle through each unit.

2. A multi-stage refrigerating system comprising a conduit, walls on either side of the conduit and spaced therefrom, reticulated means for holding absorbent material against the conduit, means for circulating a cooling fluid between the walls and over the conduit, and baffles adjacent the walls and conduit adapted to assure maximum surface contact between the said cooling fluid and the said conduit.

3. In a cooling system, the combination with a continuous air passage, of a plurality of cooling units distributed along the said passage, means comprising a cooling fluid for subjecting air in the said passage to progressively increasing cold as the said air passes through each unit, and means for circulating the cooling fluid in a closed cycle from the coldest unit through each of the remaining units, there being a sharp temperature gradient between the successive units of the system produced by substantial temperature differences between the successive units.

4. A multi-stage cooling system comprising a series of interconnected refrigerating units of progressively increasing cold, the last of the said units of the series comprising a chamber, a cooling coil within the chamber and leading unbrokenly through the remaining units of the system, a tank member com-

5 municating with the chamber, a sump communicating with the tank, a spray pipe leading from the sump and adapted to spray refrigerant over the said coil, pumping means 10 for circulating the said refrigerant from the said tank through the said spray pipe, means for imparting relatively intense cold to the said refrigerant, and means for circulating the refrigerant in a closed cycle through the preceding units of the system.

15 5. A multi-stage cooling system, which comprises the combination with an initial cooling unit, of a second unit connected therewith, the said second unit comprising a casing, a coil within the casing, a fluid absorbent medium within the casing surrounding the coil, means for countercurrently circulating refrigerating fluid through the casing around the coil, means for maintaining maximum 20 surface contact between the coil and cooling fluid, and means permitting the continuous circulation of a fluid to be cooled from the initial cooling unit through the coil of the said second unit, the said fluid to be cooled 25 sharply and abruptly differing in temperature between the successive units of the system, thereby producing a sharp temperature gradient between the units.

30 6. A multi-stage cooling system, comprising a series of interconnected refrigerating units of progressively increasing cold, the final unit of the series comprising a cooling coil for cooling air, a cooling medium for the coil, means for refrigerating the said cooling medium, a chamber adjacent the refrigerating unit, a cooling coil in the chamber leading directly into the coil of the refrigerating unit, means for maintaining a cooling fluid in intimate contact with the coil, an intake 35 conduit directly connecting with the said coil, and means for circulating in a closed cycle the refrigerated cooling medium from the final unit through each of the preceding units.

40 45 7. A multi-stage cooling system, comprising a series of interconnected refrigerating units of progressively increasing cold, the final unit of the series comprising a chamber, a cooling coil within the chamber, a tank 50 portion communicating with the chamber, a refrigerating means within the tank, a sump communicating with the tank, and means for spraying cold liquid from the sump over the cooling coil.

55 8. A multi-stage cooling system, comprising a series of interconnected refrigerating units of progressively increasing cold, the last of the said units of the series comprising a chamber, a cooling coil within the 60 chamber, a tank member communicating with the chamber, a sump communicating with the tank, refrigerating liquid within the tank and sump, a spray pipe leading from the sump and adapted to spray refrigerating liquid over the said coil, pump-

10 ing means for circulating refrigerating liquid from the said tank through the said spray pipe, and means for imparting relatively intense cold to the said refrigerating liquid.

15 9. A multi-stage cooling system, which comprises the combination with an initial cooling unit, of a second unit connected therewith and adapted to impart a progressively increasing degree of cold to a fluid stream passing through the units to an enlarged space to be cooled, the said second unit comprising a casing, a cooling coil within the casing, a liquid absorbent medium surrounding the coil, means adapted to countercurrently circulate refrigerated cooling fluid around the coil and thence through the initial unit of the system, the temperature of the cooling fluid progressively decreasing between the units of the system, means 20 adapted to increase the surface contact between the said refrigerated fluid and cooling coil, and means adapted to set up continuous and free circulation of fluid to be cooled from the initial cooling unit, and thence through the coil of the said second unit.

25 10. A multi-stage refrigerating system comprising a conduit defining a cooling coil, walls on either side of the coil and spaced therefrom, absorbent material surrounding the coil, a screen for holding absorbent material against the coil, means for circulating a cooling fluid between the walls and over the cooling coil, and means adjacent the walls and conduit for breaking up the flow of cooling fluid into swirls and eddies to assure maximum surface contact between the cooling fluid and the conduit.

30 35 In testimony whereof I affix my signature this 8th day of March, 1928.
